Inventor.

Thomas H. Brady.

By James Shepard.

Atty.

UNITED STATES PATENT OFFICE.

THOMAS H. BRADY, OF NEW BRITAIN, CONNECTICUT.

CAP-IRON FOR POLES FOR SUSPENDING ELECTRIC LIGHTS.

SPECIFICATION forming part of Letters Patent No. 339,371, dated April 6, 1886.

Application filed September 8, 1885. Serial No. 176,531. (No model.)

To all whom it may concern:

Be it known that I, THOMAS H. BRADY, a citizen of the United States, residing at New Britain, in the county of Hartford and State 5 of Connecticut, have invented certain new and useful Improvements in Cap-Irons for Poles for Suspending Electric Lights, of which the following is a specification.

In the accompanying drawings, Figure 1 is a 10 perspective view of a pole cap-iron lever for suspending an electric light, and mechanism for operating said lever. Fig. 2 is a plan view of my cap-iron for said pole. Fig. 3 is a rear elevation thereof, and Fig. 4 is a side elevation 15 of the same.

A designates a pole to be set by the roadside, and provided at the top with a cap, B, having lugs *a*, within which to pivot the lever C. The long end of this lever is provided at 20 its extremity with a cross-arm, *b*, having hooks *w*, by which to suspend the lamp so that it may swing thereon and always maintain an upright position, whether the lever C is horizontal or otherwise. The cross-arm curves 25 upward and outward, something like the horns of an ox, whereby when the lever C is horizontal in position to suspend the lamp over the street, as shown, the hood of the lamp comes under the end of the lever C and renders it 30 impossible to unhook the lamp from the arms. The shorter end of the lever C is provided with a downwardly-extending arm having an eye, *c*, to receive the rod *d*. To the lower end of this rod I attach a cord, *f*, preferably of 35 twisted wire.

To the body of the pole A, I firmly secure the frame E, upon which frame is mounted the shaft *g*, having a thread or worm thereon, and the shaft *h*, bearing the worm-gear *k* and the 40 drum *m*. One end of the cord *f* is fastened to this drum. The end of the shaft *g* is squared or otherwise formed for the ready attachment of a crank thereto.

Upon the cap B, at the side opposite the

pivotal lugs *a*, I form two upwardly-projecting lugs, *s*, between which the main rod or beam of the lever C enters when said lever is brought into a horizontal position, as shown in Fig. 1. These lugs *s* steady the lever C and prevent it from swinging around laterally 50 under the action of the wind. I also provide the cap-iron with arms *n*, for attaching the ordinary insulators and wires.

The body of the cap B is in tubular form, like a large ferrule or socket, and is designed 55 to receive the end of the pole to which it is secured. The lugs *s* have an open space between them, so that they will be less likely to become filled with snow and ice than would a notch formed in the upper side of a single 60 arm.

The weight of the lever and its appendages is sustained wholly by its pivot and the operating mechanism at the middle of the pole.

The cap is simple in construction, and can 65 be cast with its several parts all in one piece, and when cast it furnishes a cheap, convenient, and efficient means for attaching the other parts.

I have herein shown and described the 70 swinging lever and its operating mechanism only for the purpose of showing the use of the cap B. Said lever and mechanism, although of my invention, are not herein claimed, but are made the subject of another application 75 of even date herewith.

I claim as my invention—

The herein-described cap-iron for poles for suspending electric lights, the same consisting of the tubular body, the pivotal lugs *a*, the 80 insulator-arms *n*, and the upwardly-projecting lugs *s* opposite the pivotal lugs, all formed integral, substantially as described, and for the purpose specified.

THOMAS H. BRADY.
